(57) **CLAIM**

The ornamental design for a display screen or portion thereof with graphical user interface, substantially as shown and described.

DESCRIPTION

The sole FIGURE is a front view of a display screen or portion thereof with graphical user interface.

The outermost broken lines in the sole FIGURE illustrate a display screen or portion thereof with graphical user interface and form no part of the claimed design. The remaining broken lines illustrate portions of the graphical user interface and form no part of the claimed design.

1 Claim, 1 Drawing Sheet
